HANDLE CONTROL FOR ELECTRICALLY DRIVEN LIFT TRUCKS

Olov Carl Gustav Wennberg and Curt Erik
Simon Wennberg, Karlstad, SwedenApplication April 29, 1949, Serial No. 90,362
In Sweden May 7, 1948

9 Claims. (Cl. 180—65)

1

This invention relates to lift trucks and more particularly to electrically driven lift trucks of the type which is provided with an operating lever or rod swingable within a certain angle, preferably in a vertical plane, in one direction or the other. Usually such lever or rod is utilized for steering the truck in different driving directions.

The main object of the invention is to provide a suitable control mechanism for lift trucks of the type referred to above.

A further object of the invention is to provide a control mechanism for electrically motor driven lift trucks, said control mechanism comprising a blocking contrivance determining the various control positions of a control member or handle in dependence upon the positions of the operating lever within the angle in which this lever can be adjusted.

A still further object is to provide means whereby the operating handle and the operating lever are adapted to cooperate so as to obtain a reliable control of the driving means of the lift truck.

An object of the invention is also to provide a control mechanism for lift trucks in which braking of the driving means of the truck, driving at different speeds, and driving forward as well as backward may be effected dependent upon the position of the operating lever or rod within various zones of the angle, within which it can be set.

A more particular object of the invention is to provide a control mechanism for lift trucks having an operating lever being generally swingable between two extreme positions, such as a vertical position and a horizontal position. The operating lever may be adapted to cooperate with the blocking contrivance and a contact member controlled thereby so as to take the extreme position or positions within a small angle next to the same when the contact device is set to keep the motor cut off, while a braking device is preferably being engaged to prevent the truck from rolling, the motor being then stationary. These angular ranges of the operating lever may thus be designated as the braking zones. Adjacent these zones there may be a zone within the swinging ranges of the operating lever, within which a first driving speed may be switched into operation, and next to this zone there may be a zone for throwing a higher speed into service. Depending on the transmission used between the driving motor and the traction wheel of the truck, further zones of speed may be provided, if de-

2

sired. It is possible to make use of all of the zones of speed for forward drive and of all of them for backward drive.

The invention consists in the features of construction, combination of elements, and arrangements of parts as will be exemplified in the mechanism to be hereinafter described and the scope of the application of which will be indicated in the following claims.

10. In the drawings in which one embodiment of the invention is disclosed:

Figure 1 is a vertical elevation of a lift truck equipped with a control mechanism according to the invention.

15. Figure 2 is a plan view corresponding to Figure 1.

Figure 3 is a vertical section on an enlarged scale illustrating the operating lever and the parts carrying the same, said parts including a cam and a braking device.

Figure 3a is a part sectional view on line IIIa—IIIa in Fig. 3 and illustrates a detail of the braking device.

20. Figure 4 is a vertical sectional view on a plane at right angles to the section shown in Fig. 3, the upper portion of the operating lever being removed.

25. Figures 5—9 are diagrammatic representations of different positions of the operating handle of the contact device.

Figure 10 is a coupling diagram illustrating, in a simplified way, the electrical connections between the contact device and the driving motor.

30. Figure 10a is an elevation of the contact member shown in Fig. 10 as seen from the left in Fig. 10.

In the structure shown in the drawings, the lift truck broadly comprises a part adapted to receive the load, said part having two rearwardly directed legs 1 carried each by a wheel (or roller) 2, a frame 3 arranged in front of said parts, an electrical driving motor unit 4 comprising a carrying traction wheel 5 and adapted to be turned in the frame 3 about a vertical axis, the steering axis of the lift truck, and a storage battery 6 secured to the frame 3. The steering axis may be determined by a ball bearing 4a between a rotatable steering ring 4b and a stationary steering ring 4c secured to the frame 3 as shown in Fig. 3, the steering ring 4b being carried by the wheel axle journals 5a by way of journal brackets 4d. In addition to the driving motor, the motor unit comprises a transmission between the motor and the carrying traction wheel 5 and controlling means for the driving motor and the transmis-

sion. The latter is adapted to be thrown into service by electrical means, and is indicated in Fig. 3 as two belt transmissions 5b, 5c, 5d and 50a, 50b, 50c respectively. Mounted in a bearing housing 7 on the front portion of the driving motor unit 4 is an operating rod or lever 8, in a manner such that the rod is permitted to be swung about a horizontal axis of rotation 9, preferably from a vertical extreme position (full lines in Fig. 1) into a horizontal extreme position (chain-dotted lines in Fig. 1), or vice versa. The lift truck may be steered by means of the operating rod 8 in different driving directions by the turning of the driving motor unit about the vertical steering axis and, furthermore, the operating rod is used to control the driving motor and a braking device actuating the traction wheel 5. This driving motor control and actuation of the brakes is effected by the swinging of the operating rod 8 into different angular positions between said extreme positions, a contact device provided in the operating rod then permitted to be adjusted into various positions of control in dependence on the position of the operating rod within said angle. The driving motor is disengaged and the brake engaged in the extreme positions, and next to the extreme positions are the braking zones 0, 0' within which the brake is also kept engaged. If the operating rod is swung down through the braking zone 0 from the vertical extreme position and continues downward, it passes over to an angular zone I, within which the lower speed may be thrown into service by means of the contact device, and upon a continued swinging movement the operating rod is brought into an angular zone II, where the higher speed may be thrown into service. Within this zone, the lower speed also may be thrown into service instead of the higher speed, if desired. After that follows an angular zone I', within which only the lower speed can be thrown into service, and finally follows the braking range 0 adjacent to the horizontal extreme position, wherein braking takes place and the current to the driving motor is cut off. Thus, it is obvious that the truck cannot be started directly on the higher speed, it being always necessary first to throw the lower speed into service.

Now, to determine the various connecting facilities for the contact device in the various positions of the operating rod, the invention provides for a cam 10 having a configuration adapted for the object in view. The cam forms part of a blocking contrivance adapted to fix the various positions of the operating member of the contact device. In the construction shown, the operating member of the contact device comprises a handle 11 extending through the upper portion of the operating rod 8, said upper portion being formed as a hood 12 enclosing the contact device. The cam 10 is rigidly arranged on or keyed to the pin or shaft 9 fixed in the bearing housing 7 and having the operating rod 8 pivotally mounted thereon. In addition to the cam 10, the blocking contrivance comprises a blocking rod 13 arranged for cooperation with the cam, said blocking rod being axially displaceable in the operating rod 8 and formed at the top with or being adapted to be actuated by a fork 14 having a shank 15, 16 on either side of a plane containing the geometrical axis of rotation A for the operating member 11 of the contact device and the longitudinal axis of the operating rod, the operating member or handle 11 being formed within the hood 12 with a supporting

surface 17 extending at right angles or substantially so to said plane. The fork 14 may be substituted by a head 14a, Figs. 10 and 10a, having a blocking surface 14b at the top opposite the supporting surface 17, which forms the bottom of a recess 17a. The opposite short edges of the blocking surface 14b correspond to the points of the shanks 15, 16. The supporting surface 17 is intended to cooperate with the end portions or points of the fork shanks 15, 16 or of the edges of the blocking surface 14b. In the example shown in Fig. 3, the blocking rod is made in two, preferably coaxial parts, that is to say an upper part 18 formed with the fork 14 and a lower part 19, to the lower end of which is secured a guiding plunger 21 fitted into a bore 20 in the lower end portion 8' of the operating rod 8. Mounted in said guiding plunger is a roller 22 cooperating with the cam disk 10. The upper part 18 of the blocking rod is displaceably fitted into a bearing block 23 on the inside of the hood 12, and is actuated by a spring 24 arranged in said bearing block, said spring tending to move the fork 14 upwardly into abutting contact with the supporting surface 17. Provided in a guide 25 for the upper end of the lower portion 19 of the blocking rod is a spring 26 between an abutment 27 on said guide and a stop ring 28 on the portion 19, said spring tending to move the part 19 downwardly, so as to keep the roller 22 bearing on the periphery of the cam 10. There may be a small play between the ends of the rod members 18, 19 facing each other, said play permitting of being adjusted by means of an adjusting screw 29 or the like threaded into the end of one of the rod members.

In the drawings (Fig. 3), the contact device is indicated only as taking the form of a sliding contact 30 bearing on the peripheral portion of the operating handle 11 within the hood 12, but as illustrated in Figs. 10 and 10a there may be provided the number of sliding contacts 30a, 30b, 30c and contact segments 11a, 11a', 11b, 11c arranged on the operating handle and other electrical contrivances required to impart different speeds to the driving motor, or adapted to engage and disengage the latter in accordance with different angular positions of the operating handle. The contact springs 30a, 30b and 30c are each connected by a lead 60 to a controller box 61 which contains relay switches for the circuits of the electromotor 50' and their connection with the storage battery 6. Said switches and circuits are adapted to impart two different speeds to the motor, one low speed and another high speed. The controller 61 may comprise any conventional circuit, such as shown in Fig. 9 of U. S. Patent No. 2,399,605.

In the starting position illustrated, wherein the supporting surface 17 is at right angles to the longitudinal direction on the blocking rod, the contact device is taken to have cut off the current to the driving motor. At the turning of the handle 11 from this position in a clockwise direction, it is possible in dependence on the magnitude of the turning angle to throw the lower and then the higher driving speed into service for forward drive, and when the handle is turned from the starting position in a counter-clockwise direction, it is possible in a similar way to throw the lower and then the higher speed into service for backward drive, as indicated by the double arrow 31 in Fig. 3 and by the pointer 32 in Figs. 5-9. In Fig. 5, the -- position of the operating

handle is indicated at the throwing of the lower speed into service for backward drive corresponding to engagement between contact 30a and contact segment 11a', Fig. 10, and in Fig. 6 its position is indicated relative to the higher speed for backward drive corresponding to engagement between contact 30b and segment 11b. In Fig. 7, its + position is indicated for the lower speed for forward drive (30a and 11a being engaged), and in Fig. 8 the + position is indicated for the higher speed for forward drive (30c and 11c being engaged). Fig. 9 indicates the 0 position corresponding to the position of the parts in Figs. 3 and 10. In the starting position shown in Fig. 3, however, the blocking rod and its fork 14 prevent every turning movement of the handle 11, inasmuch as the shanks of the fork are abutting against the supporting surface 17 and the rod member 18 is prevented by the rod member 19 from being displaced downwardly, while the rod member 19 is kept in an upper position by means of the cam 10, inasmuch as the roller 22 is here on a circular portion 33 of the periphery of the cam 10. However, the cam is provided with a depression 34 of such configuration that, when the roller cooperates with different parts thereof, the blocking rod can be displaced downwardly, the fork 14 being consequently unable to prevent the handle 11 from being turned. Those sectors of the cam within which the latter cooperates with the roller 22 for the guidance of the blocking rod into and in different positions are denoted in Fig. 3 by 0, I, II, I', and 0', in the same manner as are the angular zones for the operating rod 8 in Fig. 1. It should be noted here that the sector II, which has a curved outline concentric to the angular arc 33, permits throwing of the lower as well as of the higher speed into service. When the operating rod 8 is swung forwardly from the vertical position shown, the roller 22 rolls down into the depression 34, so that the rod member 19 is moved by the spring 26 for a distance downwardly within the operating rod 8. The handle 11 may then be turned, but no more than permitted by the fork 14. When the handle is turned in the one or the other direction, the supporting surface 17 presses the fork downwardly, until the lower end of the fork rod 18 is stopped by the screw 29. As long as the roller 22 is within the sector I, it only permits small displacement of the blocking rod and a corresponding small turning movement of the handle 11, but when the roller reaches the sector II upon a continued downward movement of the operating rod 8, it has permitted a further displacement of the blocking rod, a further turning movement of the handle 11 being thus permitted corresponding to the lower and the higher driving speeds respectively.

The operating rod 8 is also intended to actuate the brake by means of which the traction wheel 5 of the lift truck is braked. To this end, a cam 40 is formed on the lower portion of the operating rod located in the bearing housing 17, said cam being adapted to cooperate with a roller 41 mounted on the upper end of a double-armed lever 42. This lever is mounted on a bolt 43 on the inside of the bearing housing 17, and the lower end thereof is pivotally connected to a brake arm 45 by means of a pin 44. The brake 45 is provided with a wedge-shaped end portion 46 extending in between a pair of rollers mounted at the free ends of a pair of brake shoes 48, the other ends of which are carried by fixed bearing pins 49. The brake shoes are actuated by a

spring 48' compressed by bolts 48'' for cooperation with a brake drum 50, which is secured on a counter-shaft between the motor 50' and the traction wheel 5. In the illustrated position of the operating rod 8, the roller 41 is outside the one end of the cam 40, the wedge-shaped end portion 46 of the brake arm 45 being then displaced inwardly so far as not to touch the rollers 47. This is also the case, when the operating rod takes a horizontal position. If the operating rod 8 is moved forwardly from the vertical position or upwardly from the horizontal position, the cam 40 is brought into contact with the roller 41, so that the lever 42 is swung in a clockwise direction about the bearing bolt 43, the brake arm 45 being thus pulled to the left in Fig. 3, while the wedge-shaped end portion 46 thereof forces the rollers 47 apart so as to raise the brake shoes 48 from the brake drum 50, so that the brake is disengaged. As soon as the operating rod is moved from a driving position into the vertical or horizontal position, the brake is rendered operative.

The arrangement described is distinguished not only by a simple construction, but also offers particular advantages in regard to reliable operation and simple manoeuvring, whereby manoeuvring faults are excluded as far as possible. For example, it is not possible to start the lift truck on the higher speed, it being always necessary first to switch in the lower speed. It should be noted, furthermore, that the operating handle 11 of the contact device is automatically turned back into the starting position, if the operating rod 8 is swung back to the nearest extreme position from zone II or any of the zones I and I'. This is so for the reason that the roller 22 will then be moved up toward the circular portion 33 of the cam disk to force the blocking rod with the fork 14 to exert a pressure on the supporting surface 17 on the one or the other side of the turning center of the handle 11, so that a turning moment is produced, which turns the handle back. The motor will thus always be stopped and the truck braked, when the operating rod is swung toward the extreme positions, whether the handle 11 is turned by the driver or not. Confusion between a higher and a lower speed is also excluded, when the lift truck is standing still.

What we claim is:

1. A control mechanism for electrically motor driven lift trucks, comprising an operating rod pivoted to be swingable to different intermediate positions between extreme positions within a certain angle, an adjustable operating handle mounted on the operating rod, a contact device operated by said handle to control the driving motor, and a blocking contrivance including a cam member for cooperation with said operating rod and handle to determine definite contact positions of said handle in dependence upon the angular positions of the operating rod relatively to the cam member and to prevent the handle to be set in other contact positions, said cam member and operating rod being relatively rotatable.

2. A control mechanism as claimed in claim 1, wherein said blocking contrivance is adapted to determine two extreme positions of the operating handle for every intermediate position of the operating rod, one of said extreme handle positions being a position for forward drive and the other a position for backward drive.

3. A control mechanism for motor driven lift trucks, comprising a housing, a shaft keyed to

the housing, a cam keyed to said shaft, an operating lever journalled on the shaft and pivoted to the housing to be swingable to various positions within a certain angle, an operating member mounted rotatably on said operating lever for adjustment to various operating positions corresponding to various motor speeds and driving directions, said member having a supporting surface, a blocking rod having one end portion formed with a blocking surface for cooperation with said supporting surface, said supporting surface having edges at opposite sides of a plane including the axis of rotation of the operating member, the other end portion being adapted to cooperate with the cam, the blocking rod being slidably mounted in the operating lever to take different positions relatively to said supporting surface as the operation lever is set to different angular positions relatively to the cam and the blocking rod engages different points of the cam.

4. A control mechanism as claimed in claim 3, wherein the blocking rod comprises a roller for cooperation with the cam.

5. A control mechanism as claimed in claim 3, wherein the blocking rod comprises two coaxial members, comprising a member provided with a fork, a spring the shanks of said fork being kept in engagement with the supporting surface of the operating member by the spring, a second spring and a member adapted to be moved by said second mentioned spring in a direction toward the curved surface of the cam disk, the play between the ends of said rod members facing each other being adjustable by means of a screw or the like threaded into one of the rod ends.

6. In lift trucks having a carrying wheel driven by an electric driving means for low speed drive and high speed drive, a control mechanism comprising an operating lever pivoted to be swingable to various intermediate positions between extreme positions, an adjustable operating member mounted on the operating lever, a contact device operated by said operating member to control the driving means, a blocking contrivance including an independent cam adapted to cooperate with said lever for determining definite contact positions for said contact device as switched-out positions corresponding to the extreme positions of the lever and a number of

switched-in positions corresponding to the intermediate positions of the lever, said cam and operating member being relatively rotatable, and the blocking contrivance being devised to permit

5 switching-in of only a low speed within zones of intermediate positions adjacent the extreme positions of the lever and to permit switching-in of low as well as high speeds within a zone of intermediate positions between said low speed zones.

10 7. In lift trucks having a carrying wheel driven by an electric driving means, a control mechanism comprising a housing and a shaft keyed to the housing, a cam keyed to the shaft, an operating lever pivoted to the shaft, a contact device for the operation of said driving means, a handle mounted adjustably on the operating lever, means in said lever cooperating with said cam to determine definite positions for said handle 15 and contact device in dependence upon the position of the lever relatively to the cam, said cam and operating lever being relatively rotatable, a further cam secured to the lever, a brake for the driving means and means transmitting movement from said lever cam to the brake for disengaging and engaging the brake, the lever cam being angularly disposed relative to the cam keyed to the pin or shaft whereby the engagement and disengagement of the brake is dependent on the angular position of the operating lever.

20 8. A control mechanism as claimed in claim 3, wherein the edges of the blocking surface are formed by the points of a fork at the end of the 25 blocking rod.

30 9. A control mechanism as claimed in claim 6, in which the lever includes a cam on the lower end of the lever and as a part thereof and in which brake means are provided adapted to be 35 operated by the lever through said lever cam.
